(57) **CLAIM**

The ornamental design for a bungee chair, as shown and described.

DESCRIPTION

FIG. 1 is a front perspective view of a bungee chair; FIG. 2 is a front view of the bungee chair of FIG. 1; FIG. 3 is a rear view of the bungee chair of FIG. 1; FIG. 4 is a top view of the bungee chair of FIG. 1; FIG. 5 is a left side view of the bungee chair of FIG. 1; FIG. 6 is a right side view of the bungee chair of FIG. 1; and, FIG. 7 is a bottom view of the bungee chair of FIG. 1. In FIGS. 1 through 7, the broken lines are for illustrative purposes, boundaries, and environmental structural support for the chair, and form no part of the claimed design.
